(57) **CLAIM**

The ornamental design for a charging device as shown and described.

DESCRIPTION

FIG. 1 is a back view of the charging device showing my new design.

FIG. 2 is a front view thereof;

FIG. 3 is a left side view thereof;

FIG. 4 is right side view thereof;

FIG. 5 is a top view thereof; and,

FIG. 6 is a bottom view thereof.

The broken lines depict portions of the ‘charging device’ that form no part of the claimed design.
